ENGINE HEAD LIFTING TOOL

Alvah R. Cheek, Thurman, Iowa

Application October 23, 1946, Serial No. 705,001

5 Claims. (Cl. 294—15)

1

This invention relates to a cylinder head lifting tool and more particularly to a tool for lifting the cylinder heads of engines of the valve-in-head type, such as of the engines used at present in Buick motor cars.

It is an object of this invention to provide a cylinder head lifting tool which is simple and inexpensive in nature and can be attached to the cylinder head to be removed from its cylinder block in a simple and rapid manner.

It is a further object of the invention to provide a cylinder head lifting tool which can be attached to the cylinder head with the aid of such fastening means only as are present on the cylinder head anyhow.

It is another object of the invention to provide a cylinder head lifting tool in the form of a rectangular frame which has a central portion that serves as a carrying handle and which can be rigidly spaced from the top surface of the cylinder head.

Still another object of the invention resides in the provision of a cylinder head lifting tool comprising a rectangular frame whose length is adjustable in a symmetrical manner relative to the aforementioned central carrying handle so that the weight of the cylinder head remains symmetrically distributed relative to said carrying handle regardless to what length of cylinder head the tool has to be adjusted.

Still another object of the invention is the provision of a cylinder head lifting tool comprising a frame composed of a rectangular frame which, while adjustable at least in the longitudinal direction, is rigid when so adjusted and two links which can be tightly fastened to one of the two longitudinal sides of said rectangular frame and to one side of the cylinder head to form a rigid support for the cylinder head also when the frame is used to serve as a stand for the cylinder head in upside-down position. When the tool is removed from the cylinder head these links may be folded down upon said frame so that they do not protrude beyond the height of the latter.

Other objects of the invention will appear as the description proceeds, reference being had to the accompanying drawing, in which—

Fig. 1 is a perspective view of a cylinder head lifting tool according to the invention, showing this tool attached to a cylinder head belonging to a motor car engine of the valve-in-head type.

Fig. 2 shows the arrangement of Fig. 1 in a side elevational view;

Fig. 3 shows in a perspective view the cylinder head lifting tool of Fig. 1 in upside-down position;

2

wherein the tool serves as a support or stand for the cylinder head; and

Fig. 4 is a plan view, at a slightly reduced scale, of the head lifting tool.

In the drawing, 10 denotes the cylinder head of a motor car engine of the valve-in-head type. By way of example the cylinder head of a Buick machine is diagrammatically indicated. In Figs. 1 to 3 the lifting tool is shown attached to the cylinder head, this tool consisting basically of a rectangular frame 11, two links 12 and 13, and a central handle member 14.

The rectangular frame 11 is composed of six parts, namely two T-shaped elements 14', 14'', forming together an H-shaped central member 14, and four L-shaped members 15, 16, 17 and 18. The members 15 and 16 form together a U-shaped frame portion which is slideably mounted on the legs 19 and 20 of the H-shaped central member 14, whereas the two other L-shaped members 17 and 18 form together another U-shaped frame portion which is slideably mounted on the legs 21 and 22 of the H-shaped central member 14. Set screws 23, 24, 25 and 26 serve to secure the U-shaped frame portions on the central member 14. When the set screws 23 to 26 are loosened the two U-shaped frame portions of the frame 11 can be shifted lengthwise on the legs 19 to 22 of the H-shaped central member 14 for adjusting the frame to any desired length, whereupon said set screws are tightened to keep the frame at the chosen length. It will be seen that the two U-shaped frame portions are adjustable relative to the central member 14 independently of one another, and that regardless of the length of the frame to be used they always can be adjusted so as to extend symmetrically relative to the central member 14.

The frame 11 is also adjustable in the transverse direction. For this purpose one leg 27 of the L-shaped member 16 fits slideably into a tubular leg 29 of the L-shaped member 15, whereas a leg 28 of the member 18 slideably fits into a tubular leg 30 of the member 17 and leg 31'' of the T-shaped element 14'' slideably fits into the leg 31' of the other T-shaped element 14' of the central member 14. Set screws 32, 33 and 34 are provided for keeping the frame 11 at the adjusted width.

Fig. 4 shows in full lines the frame 11 as adjusted to its smallest size in the longitudinal direction as well as in the transverse direction, whereas it shows in dot and dash lines the frame adjusted to a larger size in the longitudinal as well as in the transverse direction. Thus, the

size of the frame can be changed to fit cylinder heads of widely different lengths and/or widths without disturbing the symmetrical arrangement relative to the central handle 14.

The legs 29' and 30' of the L-shaped frame members 15 and 17 at one side of the frame 11 are provided with slots 35 extending completely through said legs in a plane perpendicular to the plane of the frame 11. These slots permit for the passage of stud bolts 36 which in the type of cylinder head shown are part not of the tool but of the cylinder head and extend out from the top thereof. Nuts 37 which are also part of the car engine are screwed on the top end of the stud bolts 36 to limit movement of the frame 11 away from the cylinder head. The arrangement of two slots 35 of appreciable length on each leg 29' and 30' of the frame 11 in combination with the adjustability of the length of the frame permits the use of the tool for any distance the two stud bolts 36 have on conventional motor car engines.

While the slots 35 are arranged in the one longitudinal side of the frame 11, the links 12 and 13 are fastened at one end to the other longitudinal side of the frame by means of screws 38 passing each through a hole 39 in the frame members 16 and 18. There are several holes 39 provided in the frame for each link 12 and 13, five such holes 39 being shown for each link in the example illustrated in the drawing. The lower end of each link 12, 13 contains one or more holes 40 for the passage of a screw 41 by means of which these links may be screwed to the side of the cylinder head. In the example shown there are three holes 40 in each link 12 and 13 and the places at which these links are secured to the side of the motor may be chosen by selecting two of the screw holes present in the manifold base usually found on conventional engine heads. The screws 41 are screws which on the cylinder head are ordinarily used to fasten the manifold. The length of the links 12 and 13 is conveniently chosen so that when these links are attached to the engine head and the frame in the manner shown in full lines in Figs. 1 to 3, that is to say, the screws 41 are passed through the lowermost of the holes 40 in the links 12, 13 and the screws 38 through the outermost of the holes 39 in the frame 11, with the length of the frame being adjusted so that the links 12 and 13 are in a vertical position, even the longest stud-bolts 36 used on conventional machines will extend above the frame 11 substantially only for the length which is necessary to take the nuts 37. For shorter stud bolts 36 the active height of the links 12, 13 can be reduced by passing the screws 41 through another of the holes 40 and by using the links 12, 13 in an inclined position such as indicated in an exemplifying manner in dot and dash lines in Fig. 2. Any two of the manifold screw holes may be used for the attachment of the links 12 and 13 as is also indicated in dot and dash lines in Fig. 2, but in general such a pair of holes will be always chosen which is symmetrical relative to the center of the engine head in order to have the load as equally as possible divided with respect to the central member 14 of the frame 11.

When the tool is attached to the cylinder head as shown in Figs. 1 and 2, the cylinder head can be removed from the cylinder block by grasping the central member 14 which serves as a carrying handle. After having carried the cylinder head by means of the lifting tool to the place where

work on the cylinder head, e. g. on the valve seats, is to be performed, the tool together with the cylinder head is turned upside-down into the position shown in Fig. 3 in which position the tool forms a rigid stand for the cylinder head while work is done upon the latter.

When it is desired to place the cylinder head back upon the cylinder block, the cylinder head together with the tool is turned back into the position of Fig. 1, the handle 14 is grasped and the cylinder head is carried by means of the tool to the cylinder block and properly positioned thereon. Then, the nuts 37 and screws 41 are taken off so that the tool can be removed from the cylinder head. Conveniently, also the screws 38 are loosened somewhat so that the links 12, 13 can be swung into the position in which they lie alongside the frame 11. The complete tool can now be stored away with very small space requirement, such as in a drawer of a height only slightly greater than the diameter of the frame portions 29 or 30.

While I have shown and described one particular embodiment of the invention I desire it to be understood that this embodiment has been given by way of example only since various changes and modifications may be made in the details of the construction without departing from the spirit of the invention or the scope of the appended claims.

What I claim is:

1. A cylinder head lifting tool comprising a frame composed of an H-shaped central member and two U-shaped frame portions, one to each side of said H-shaped central member, said U-shaped frame portions being each telescopically adjustable relative to the parallel legs of said H-shaped central member so as to permit adjustment of the length of the frame symmetrically with respect to said central member, and said two U-shaped frame portions as well as said H-shaped central member being each composed of two elements telescopically united for adjustability in the transverse direction of the frame.

2. A cylinder head lifting tool comprising a rectangular frame adjustable at least in the lengthwise direction, slots in one of the two longitudinal sides of said rectangular frame extending through said longitudinal side in a plane perpendicular to the plane of said frame to permit the passage of stud-bolts extending out of the top of said cylinder head, two links attached to the other of said two longitudinal sides of said frame and also extending in a plane perpendicular to the plane of said frame, and means provided at the free end of each link for the attachment of the latter to the side of the cylinder head.

3. A cylinder head lifting tool comprising a frame composed of an H-shaped central member and two U-shaped frame portions, one to each side of said H-shaped central member, said U-shaped frame portions being each telescopically adjustable relative to the parallel legs of said H-shaped central member so as to permit adjustment of the length of the frame symmetrically with respect to said central member, two links attached to one of the two longitudinal sides of said frame and extending in a plane perpendicular to the plane of said frame, and means provided at the free end of each link for the attachment of the latter to the side of the cylinder head.

4. A cylinder head lifting device comprising a frame composed of an H-shaped central member and two U-shaped frame portions, one to each side of said H-shaped central member, said U-

shaped frame portions being each telescopically adjustable relative to the parallel legs of said H-shaped central member so as to permit adjustment of the length of the frame symmetrically to said central member, slots in one of the two longitudinal sides of said frame extending through said longitudinal side in a plane perpendicular to the plane of said frame to permit the passage through said slots of stud-bolts extending out of the top of said cylinder head, two links attached to the other of said two longitudinal sides of said frame and extending in a plane perpendicular to the plane of said frame, and means provided at the free end of each link for the attachment of the latter to the side of the cylinder head.

5. A cylinder head lifting tool comprising a frame composed of an H-shaped central member and two U-shaped frame portions, one to each side of said H-shaped central member, said U-shaped frame portions being each telescopically adjustable relative to the parallel legs of said H-shaped central member so as to permit adjustment of the length of the frame symmetrically to said central member, slots in one of the two longitudinal sides of said frame extending through said longitudinal side in a plane perpendicular to the plane of said frame to per-

mit the passage through said slots of stud-bolts extending out of the top of said cylinder head, two links attached in a tightenable manner to the other of said two longitudinal sides of said frame and extending in a plane perpendicular to the plane of said frame, and means provided at the free end of each link for the attachment of the latter to the side of the cylinder head, said links rigidly supporting said frame in a position parallel to the top surface of the cylinder head at a distance therefrom when these links are tightened on said longitudinal side of the frame and said side of the cylinder head, but being foldable upon said frame when the tool is removed from the cylinder head.
